UNITED STATES PATENT OFFICE

127,647

DESIGN FOR A CAPE

Alice A. Tucker, Grosse Pointe Farms, Mich.

Application December 30, 1940, Serial No. 97,724

Term of patent 7 years

To all whom it may concern:

Be it known that I, Alice A. Tucker, a citizen of the United States, residing at 76 Kerby, Grosse Pointe Farms, in the county of Wayne and State of Michigan, have invented a new, original, and ornamental Design for a Cape, of which the following is a specification, reference being had to the accompanying drawing, forming part thereof.

In the drawing:

Fig. 1 is a front elevational view of a cape showing my new design;

Fig. 2 is a rear elevational view of the same.

I claim:

The ornamental design for a cape, as shown.

ALICE A. TUCKER.
